UNITED STATES PATENT OFFICE.

ABRAM TOLKOWSKY, MAURICE TOLKOWSKY, AND ISIDORE TOLKOWSKY,
OF ANTWERP, BELGIUM.

DESIGN FOR A CUT STONE.

SPECIFICATION forming part of Design No. 36,340, dated June 2, 1903.

Application filed October 28, 1902. Serial No. 129,179. Term of patent 3½ years.

To all whom it may concern:

Be it known that we, ABRAM TOLKOWSKY, MAURICE TOLKOWSKY, and ISIDORE TOLKOWSKY, subjects of the Emperor of Russia, residing in Antwerp, Belgium, have invented a certain new, original, and ornamental design for Cut Stones, of which the following is a specification, reference being had to the accompanying drawings, forming a part thereof. Figure 1 is a top plan view of a cut stone, showing our new design. Fig. 2 is an underneath view of the same, and Fig. 3 is a side view.

Having thus fully described our invention,

what we claim as new, and desire to secure by 15 Letters Patent, is—

The ornamental design for a cut stone as herein shown.

In testimony that we, undersigned, claim the foregoing we have hereunto set our hands 20 this 15th day of October, 1902.
